No. 727,360.

PATENTED MAY 5, 1903.

H. M. HILL.
ELECTRICAL WATER HEATER.
APPLICATION FILED MAR. 31, 1902.

NO MODEL.

UNITED STATES PATENT OFFICE.

HARRY M. HILL, OF ST. LOUIS, MISSOURI, ASSIGNOR TO HILL ELECTRICAL MANUFACTURING COMPANY, OF ST. LOUIS, MISSOURI, A CORPORATION OF MISSOURI.

ELECTRICAL WATER-HEATER.

SPECIFICATION forming part of Letters Patent No. 727,360, dated May 5, 1903.

Application filed March 31, 1902. Serial No. 100,740. (No model.)

To all whom it may concern:

Be it known that I, HARRY M. HILL, a citizen of the United States, residing at St. Louis, State of Missouri, have invented a certain new and useful Improvement in Electrical Water-Heaters, of which the following is a full, clear, and exact description, such as will enable others skilled in the art to which it appertains to make and use the same, reference being had

to the accompanying drawings, forming part of this specification, in which—

Figure 1 is a side elevational view of my improved electrical water-heater. Fig. 2 is a vertical sectional view through the same. Fig. 3 is a cross-sectional view on line 3-3 of Fig. 2. Fig. 4 is an elevational view of one of the electrodes. Fig. 5 is an elevational view of the other electrode, and Fig. 6 is a bottom plan view of the centering-disk.

This invention relates to a new and useful improvement in electrical water-heaters of that class shown in United States Letters Patent No. 678,314, granted to me July 9, 1901.

My present invention consists in the construction, arrangement, and combination of the several parts, all as will hereinafter be described and afterward pointed out in the claims.

In the drawings, 1 indicates a stand-pipe for water, the same being arranged in an ordinary pipe system. The upper end of this stand-pipe is shown as being curved to form a gooseneck, the end thereof carrying a spigot 2, manipulated by a handle 3. The spigot stem is provided with a key 4, fitting in a slot in a switch-stem 5, said switch being inclosed in a casing 6, supported by a bracket 7 upon the stand-pipe.

Referring to Fig. 2, 9 indicates a coupling which is screwed in the lower end of the spigot, into which coupling is fitted a head 11, made of insulation material. 12 indicates a flanged boss secured to the under side of the head 11, said coupling 9, head 11, and flanged boss 12 being provided with alining openings for the passage of water. A wire 8 leads to the flanged boss 12. The purpose of thus separating the coupling 9 and the flanged boss 12 is to insulate the apparatus from the water-pipe.

13 indicates an electrode, which for the sake of distinction will be termed the "inner" electrode, the same being provided with a bore for the passage of water, whereby the water is caused to pass downwardly through this 55 inner electrode and be distributed by means of a centering-head 14, of insulation material, at different points outside of the central or core electrode.

The insulation centering-disk referred to is 60 preferably screwed into the lower end of the electrode 13 and is provided with radial grooves 15 on its under face, (see Fig. 6,) which connect with vertical side grooves 16 at its periphery. (See Figs. 2 and 5.) In this 65 manner the water is distributed around the periphery of the centering-disk and directed upwardly at different points outside of the central electrode.

17 indicates what I will term an "outer" 70 or "encircling" electrode, which is preferably formed with an imperforate bottom, as shown, and an inner bore whose diameter corresponds to the diameter of the insulation centering-disk 14. In this manner the electrode 17 75 forms the bottom and side walls for the grooves 15 and 16, respectively. The upper end of electrode 17 is open for obvious reasons and is designed to abut against the under face of the insulation-head 11. Openings 18 are 80 formed in the side walls of electrode 17 near its upper end for the escape of water passing between the inner and outer electrodes.

The outer side face of electrode 17 is corrugated or provided with a series of grooves 85 19, (see Fig. 4,) the external diameter being reduced at the upper end of said electrode 17 to form shoulders 20, which support an imperforate hood-ring 21. This ring or band 21 extends above the upper end of electrode 17 90 and is received in a concentric groove 22 in the under face of the insulation-head 11. A wire 23 is connected to this band for supplying the current to the outer electrode. A thimble or binding-post 24 is secured to the 95 band 21 and extends laterally therefrom, as shown in Fig. 2, for forming a connection with wire 23, and by means of this thimble the electrode 17 is held in position.

25 indicates a housing received in a con- 100

centric groove 26 in the insulation-head 11, said housing being of larger diameter than the outer electrode, so as to provide a passage for the heated water. This housing is slotted 5 for the reception of thimble 24, as shown at 27 in Fig. 2, and when the housing is in position screws 28 (see Fig. 1) are employed to hold said housing in place.

In operation the act of admitting water to 10 the heater by turning the spigot throws a switch and completes the circuit. Water passing through the bore in the central electrode is distributed by the centering-disk at different points between the inner and outer electrodes, where it is heated, the water then rising and overflowing through the lateral openings 18. Striking the band 21 it is directed 15 downwardly into the housing 25, which housing serves as a funnel to collect the heated water and discharge it through the opening in its bottom. The upper end of the housing opens to atmosphere through the slot 27, and consequently there is no danger of steam generated by the heated water forming a trap 20 and exerting a back pressure to interfere with the operation of the device.

I am aware that many minor changes in the construction, arrangement, and combination of the several parts of my device can be made 30 and substituted for those herein shown and described without in the least departing from the nature and principle of my invention.

Having thus described my invention, what I claim as new, and desire to secure by Letters 35 Patent, is—

1. In an electrical water-heater, the combination with an outer electrode, of an inner electrode therein, both of said electrodes having water-passages therethrough, and a discharge-shell surrounding said electrodes, 40 forming therewith a water-channel, between said outer electrode and said shell; substantially as described.

2. In an electrical water-heater, the combination with an outer electrode, of an inner electrode therein, both of said electrodes having water-passages therethrough, and centering means for said inner electrode with radial channels therein; substantially as described.

3. In an electrical water-heater, the combination with a head, of two concentrically-arranged electrodes supported at one of their ends thereby, both of said electrodes having a water-passage entirely therethrough, and 55 a shell connected with said head, forming, with said outer electrode, a passage for water therebetween; substantially as described.

4. In an electrical water-heater, the combination with a support through which is formed 60 a passage for liquid, of an electrode arranged on said support and formed with a registering passage for the liquid, and an inclosing electrode having an imperforate bottom integral therewith, whereby the liquid passes up 65 in the space between the inner and outer electrodes and overflows through an opening in

the upper portion of the outer electrode; substantially as described.

5. In an electrical water-heater, the combination with an insulation-support, of electrodes mounted thereon, one of said electrodes being contained within the other, said contained electrode being formed with a passage for liquid therethrough, and a centering-head with opening therethrough for directing 75 the liquid passing through said passage into the space between said electrodes; substantially as described.

6. In an electrical water-heater, the combination with two electrodes, of means for supporting one of said electrodes at both ends within the other of said electrodes, said contained electrode being formed with a passage for liquid, one of the end supports for said contained electrode being provided with passages for distributing liquid in the space between said electrodes; substantially as described.

7. In an electrical water-heater, the combination with containing and contained electrodes, the contained electrode being provided with a passage for liquid and the containing electrode having a closed lower end, and being provided with openings which lead from the upper portion of the space between said 95 electrodes to atmosphere, and means for supporting said electrodes; substantially as described.

8. In an electrical water-heater, the combination with inner and outer electrodes, the inner electrode having a passage for liquid, a support therefor having a registering passage, a series of openings in the outer electrode leading from the upper end of the space between said electrodes, and means at the upper end of the outer electrode for securing the same to said support; substantially as described.

9. In an electrical water-heater, the combination with inner and outer electrodes, the former being provided with a passage for liquid and the latter being formed with an imperforate bottom, and an insulation centering-disk provided with a passage for liquid between the inner electrode and the imperforate bottom of the outer electrode; substantially as described.

10. In an electrical water-heater, the combination with inner and outer electrodes, of means for supporting the same, the outer 120 electrode having grooves in its outer periphery, and an encircling band; substantially as described.

11. In an electrical water-heater, the combination with an insulation supporting-disk, of inner and outer electrodes carried thereby, and a shell inclosing said electrodes and forming a space therebetween and the outer electrode, said shell being also carried by said insulation supporting-disk; substantially as 130 described.

12. In an electrical water-heater, the combi-

nation with an insulation supporting-disk, of inner and outer electrodes with a water-passage entirely through both electrodes carried thereby, a shell inclosing said electrodes, and

5 an opening for establishing communication between the upper end of the space within said shell and atmosphere; substantially as described.

13. In an electrical water-heater, the combination with inner and outer electrodes, of means for supporting the same, the outer electrode being formed with grooves in its outer periphery, said periphery being of different diameters so as to provide a shoulder, and an 15 encircling band around the smaller diameter and supported by said shoulder; substantially as described.

14. In an electrical water-heater, the combination with a coupling 9, of an insulation-head 11 supported thereby, a threaded boss attached to said insulation-head, and an electrode carried by said threaded boss; substantially as described.

15. In an electrical water-heater, the combination with a coupling, of an insulation-head

and an electrode carried thereby, and an inclosing electrode having an encircling band which is received in a groove in said insulation-head; substantially as described.

16. In an electrical water-heater, the combination with an insulation-head, of inner and outer electrodes, an encircling band on said outer electrode, a projection 24 extending from said encircling band, an inclosing shell 25, and means for securing the inclosing shell 35 to the head; substantially as described.

17. In an electrical water-heater, a plurality of concentrically-arranged electrodes, each of which has a water-passage extending therethrough, and centering means provided with 40 vertical and radial water-channels rigidly supporting said electrodes in fixed relation to each other; substantially as described.

In testimony whereof I hereunto affix my signature, in the presence of two witnesses, 45 this 27th day of March, 1902.

HARRY M. HILL.
